UNITED STATES PATENT OFFICE.

NORMAN B. WARD, OF BEN AVON, PENNSYLVANIA.

TOP.

Application filed September 23, 1925. Serial No. 58,062.

My invention relates to improvements in tops, and particularly in tops such as are shown in Letters Patent of the United States No. 685,311, granted October 29, 1901.

5 In the accompanying drawings, Fig. I is a view of the assembled top in side elevation; Fig. II is a view of it in axial section; Fig. III is a view in plan from beneath.

The top consists of a body portion 1, and 10 a two-part stem 2, 3. The body includes an axially perforate hub 11 and a conical web to which in the drawings the numeral 1 is immediately applied, terminating in a weighted rim 12. The two parts of the stem 15 telescope one into the other, as is clearly seen in Fig. II, and opposite shoulders 20 and 30 are formed which define the position of the body member upon the stem. The distance between these shoulders is fixed by the abut- 20 ment of the lower end of the stem part 2 upon the bottom of the bore in stem part 3. It will be observed that the vertical depth of the hub 11 of the body portion, as seen in Fig. II should not exceed the space interval 25 between the shoulders 20 and 30 of the assembled stem, but should in fact be sufficiently less to give clearance and free turning. Such nicety of proportion becomes possible in the practice of my invention. Of the 30 stem it suffices to add that its parts are formed from wire in an automatic machine, and the shaping is essentially that of lathe turning.

The hub 11 exteriorly is polygonal in 35 cross-section, to afford firmer hold of the string wound upon it to spin it.

The conical web 1 is shown to be banded externally with concentric rings 13. These 40 are a matter of ornamentation merely, and suggest that between the rings the surface may be variously colored.

It has not hitherto been possible to produce the top of the patent alluded to above, with commercial success. All attempts to 45 do so have failed, because of the impossibility of producing at a permissible cost a top body having the characteristics set forth in the patent, and in dimension responsive with sufficient accuracy to specification. It 50 has hitherto been deemed necessary to the production of such a top for the market, that its body be formed of cast iron. And in forming the body of cast iron it has been

found a practical necessity that the hub be cast initially solid and imperforate, and that 55 in an ensuing operation an axial bore be drilled through the hub for the passage of the stem. It has been found impossible to obtain iron castings for the bodies of such tops so accurate in their proportions as to 60 be serviceable. The casting shrinks in cooling and the shrinkage is irregular, and two particular difficulties were in fact encountered, one, that the hubs of a series of castings could not be drilled axially with pre- 65 cision; and, second, that the hubs were so various in length that the body of the top could not certainly turn freely between the two sections of the stem when these were telescoped together. The best efforts to 70 manufacture the tops of the patent under these, the only possible recognized conditions, resulted in rejections to the extent of thirty per cent of the product. This was impossible, and attempts to manufacture 75 were given up.

I have discovered that by forming the top bodies as die castings and of a non-shrinkable metal, I can not only get a product uniformly accurate in its proportions and responsive to specification, but I can actually produce the top body with the bore for the stem formed within it when the body itself is initially formed. Thus I dispense with the separate and succeeding and expensive 80 and hitherto inaccurate step of drilling a bore through the hub. I preferably employ as the non-shrinkable metal out of which I form the top body an alloy of zinc base. And I produce an article of such accuracy in 85 shape and proportion that practically none are rejected, and commercial production becomes possible. Incidentally, I have improved the shape of the top in detail.

90 Operation is manifest. The spinning string is wound externally upon hub 11. The parts then being in the position shown in Figs. I and II, the spinner rests the top on its lower spinning point on a suitable surface, and holding the top erect by means of the upper stem section, he presses the stem firmly downward to gain the necessary 95 rigidity. He then pulls the string and so sets the body portion to spinning, and then he releases the stem. It is in consequence of 100 the clearance above and below for the hub 105

of the body portion between the shoulders 20 and 30, that satisfactory operation is assured.

The top may be spun equally well in inverted position.

I claim as my invention:

A top including a two-part telescopic stem

and a top body formed of non-shrinkable metal shaped by die-casting with an axial perforation, rotatably mounted upon said stem. 10

In testimony whereof I have hereunto set my hand.

NORMAN B. WARD.
